UNITED STATES PATENT OFFICE.

PHINEAS H. ADAMS, OF CHICAGO, ILLINOIS, ASSIGNOR TO EDMOND C. PECK,
OF SAME PLACE.

CENTRIFUGAL SEPARATOR.

SPECIFICATION forming part of Letters Patent No. 668,747, dated February 26, 1901.

Application filed February 21, 1900. Serial No. 6,066. (No model.)

To all whom it may concern:

Be it known that I, PHINEAS H. ADAMS, a citizen of the United States, residing at Chicago, in the county of Cook and State of Illinois, have invented a new and useful Improvement 5 in Centrifugal Separators, of which the following is a specification.

My invention relates more particularly to improvements in the art of centrifugal separation or concentration of material while in a finely-divided state and in the presence of or mixed with water; and it consists in various details of construction of a machine for use in this art.

15 In centrifugal apparatus which are rotated at comparatively high speeds and which consist of heavy vessels and other rotatable parts or contain considerable weights of the mixture treated the vibration which arises is liable to be destructive to the supporting-shaft and bearings and unfavorable to the best operation of the machine; and one of the objects of this invention is to provide the type of machine having a plurality of rotating parts with 20 yielding supports, by which the objectionable vibration is absorbed.

Another object of the invention is to so support a centrifugal separator which rotates about a vertical axis that the shafting and 30 belting for actuating its moving parts shall be removed from above the floor of the mill, where they are dangerous and occupy much space.

The above and other ends are attained by 35 the mechanism hereinafter described and claimed.

In the drawings, Figure 1 illustrates a central vertical longitudinal section of my improved separator; and Fig. 2 is a sectional 40 detail of the bearing 22, taken at right angles to Fig. 1.

10 designates a rotatable treatment vessel or cylinder having its axis vertical and consisting of two heads 10^a 10^b and an intermediate cylindrical or frusto-conical portion, the 45 lower head 10^a being provided with a downwardly-projecting hollow shaft or hub 11, stepped on antifriction-bearing 12, carried by a movable plate 12^a, which slides freely upon 50 a portion of the base of the machine corresponding in shape to the under side of the

plate. The upper head 10^b of the vessel is provided with a feed-receptacle 13, into which 55 delivers a pipe or conduit, the material fed thereby passing through feed-orifices 14 in the head of the vessel, at or near the periphery of the receptacle. After treatment within the vessel the separated material is discharged through peripheral orifices 15 near the lower end thereof into the outer section 60 of a double trough 15^a, the inner section of which receives any excess of liquid or any splashing or back pressure of the pulp discharged through openings 15^b in the head of the vessel. This trough is also so formed 65 that it serves as a base and support for the machine. The treatment vessel is rotated at a speed necessary to generate the desired degree of centrifugal force by a pulley 11^a, belted to a pulley 11^b upon a counter-shaft 11^c, 70 suitably supported below the floor of the mill. This counter-shaft is in turn driven by a pulley 11^d, belted to a source of power.

Within the treatment vessel is a deflector or cylinder 16, of any suitable construction, 75 which is supported by spiders 17 17 upon a shaft 18, passing axially through the vessel and having a bearing in an inwardly-projecting hub 19, secured to or integral with the head 10^b, thus furnishing a lateral support for 80 the treatment vessel at this end, and also in the hollow shaft 11 of this vessel. Sleeves 19^a are mounted upon the inside of the head and upon the deflector-spiders, which, surrounding one another and the journals with 85 in the hubs 11 and 19, serve to protect them from dirt. The shaft 18 is also journaled in the support 12^a of the treatment vessel and in a bearing 20, mounted upon a ball-and-socket or other universal support held in a 90 bracket 12, depending from the base of the machine, and at its extreme lower end in an antifriction step-bearing 22. This step is preferably supported by pivoted links from a lever 23, fulcrumed on the bracket 21. The 95 opposite end of the lever contacts, through a suitable roll carried thereby, with a cam 24, continuously rotated by a slow-down worm-gearing 25, driven by a pulley 25^a, which is belted to a pulley 25^b on the counter-shaft 11^c. 100 This cam mechanism effects a periodic longitudinal movement of the deflector within

the vessel to permit and assist in the separation and discharge of material in a manner so well known that it will not be necessary to describe. The deflector is rotated at a different speed from the treatment vessel by a pulley 18^a, belted to a pulley 18^b on the counter-shaft.

In the base of the machine, surrounding a hub 26, extended downwardly from the step-
10 plate 12^a through an opening, are recesses 27, in which are seated spiral springs 28, pressing at one end against the hub 26 and being held in place by bosses 29 thereon and having their opposite ends resting upon movable heads or followers in the recesses. Against these heads bear screws 30, threaded through the ends of the recesses, serving to adjust the tension of the springs. Now, noting that the plate 12^a and the surface which supports it
15 are curved upon the arc of a circle the center of which lies at the center of the universal bearing 20 of the deflector-shaft and also that the pivoted support of the step 22 allows some lateral play, it will be seen that the treatment vessel and deflector are free to yield or sway transversely together in any direction, while being normally maintained in a vertical position by the pressure of the springs. Thus the vibration set up by the rotation of the two
20 elements is absorbed. To equalize the belt-pull upon the side of the vessel toward the counter-shaft, the spring on that side may be more compressed by its adjusting-screw than the others, or, as illustrated, a stronger spring,
25 having greater resistance, may be used. It will be further seen that the driving-gear of the separator is so arranged that the floor is free from the belts and shafting, resulting in economy of space and freedom from danger
30 to persons passing among the machines.

As the process of the separation of material within machines of this character is familiar and as the elements more directly connected therewith form no part of this invention, no
45 description of the operation will be given.

What I claim as my invention, and desire to secure by Letters Patent, is—

1. In a centrifugal separator, the combination of a rotatable treatment vessel, an independently-rotatable deflector therein, and transversely-movable bearings in which the vessel and deflector are mounted whereby a transverse movement of both is permitted, substantially as described.

5 2. In a centrifugal separator, the combination of a rotatable treatment vessel, an independently-rotatable deflector therein, transversely-movable bearings in which the vessel and deflector are mounted whereby a trans-
60 verse movement of both is permitted, and yieldable means to resist said movement, substantially as described.

3. In a centrifugal separator, the combination of a rotatable treatment vessel, an independently-rotatable deflector therein, transversely-movable bearings in which the vessel and deflector are mounted whereby a trans-

verse movement of both is permitted, and adjustable yieldable means to resist said movement, substantially as described.

4. In a centrifugal separator, the combination of a rotatable treatment vessel, an independently-rotatable deflector therein, movable bearings in which the vessel and deflector are mounted whereby a transverse movement of both is permitted, and yieldable means of unequal resistance to oppose said movement in different directions, substantially as described.

5. In a centrifugal separator, the combination of a rotatable treatment vessel, an independently-rotatable and longitudinally-movable deflector therein, and transversely-movable bearings in which the vessel and deflector are mounted whereby a transverse movement of both and the longitudinal movement of the deflector are permitted, substantially as described.

6. In a centrifugal separator, the combination of a rotatable treatment vessel, a transversely-movable bearing therefor, an independently-rotatable deflector within said vessel, and a shaft upon which the deflector is mounted journaled in a portion of the vessel and in its movable bearing, substantially as described.

7. In a centrifugal separator, the combination of a rotatable treatment vessel, a transversely-movable bearing therefor, an independently-rotatable deflector within said vessel, a shaft upon which the deflector is mounted journaled in a portion of the vessel and in its movable bearing, and springs surrounding the bearing of the vessel to resist its movement, substantially as described.

8. In a centrifugal separator, the combination of a rotatable treatment vessel, a transversely-movable bearing therefor, an independently-rotatable deflector within said vessel, a shaft upon which the deflector is mounted journaled in a portion of the vessel and in its movable bearing, and springs of different strength surrounding the bearing of the vessel to resist its movement, substantially as described.

9. In a centrifugal separator, the combination of a rotatable treatment vessel, a transversely-movable bearing therefor, an independently-rotatable deflector within said vessel, and a shaft upon which the deflector is mounted journaled in a portion of the vessel, in its movable bearing and also an independently-movable bearing, substantially as described.

10. In a centrifugal separator, the combination of a rotatable treatment vessel, a transversely-movable bearing therefor, an independently-rotatable and longitudinally-movable deflector within said vessel, a shaft upon which the deflector is mounted journaled in a portion of the vessel and in its movable bearing, and means acting upon the deflector-shaft whereby its longitudinal movement is secured, substantially as described.

11. In a centrifugal separator, the combination of a rotatable treatment vessel, a transversely-movable bearing therefor, an independently-rotatable and longitudinally-movable deflector within said vessel, a shaft upon which the deflector is mounted, and a transversely and longitudinally movable bearing for said deflector-shaft, substantially as described. 40
12. In a centrifugal separator, the combination of a rotatable treatment vessel, a hollow shaft extending from the lower end thereof, a transversely-movable step upon which the vessel is supported, springs to resist the movement of said shaft, an independently-rotatable deflector within the treatment vessel, a shaft upon which the deflector is mounted, said shaft extending through the vessel shaft and step and having a bearing therein, a universal bearing for the deflector-shaft below the step of the vessel, and a longitudinally-movable step to receive the lower end of the deflector-shaft, substantially as described. 50
13. In a centrifugal separator, the combination of a treatment vessel rotatable about a vertical axis, a hollow shaft extending from the lower end of the vessel through the floor upon which the separator is supported and there stepped in a suitable bearing and provided with a pulley, an independently-rotatable deflector within the treatment vessel, a shaft therefor extending through the shaft and step of the vessel and journaled in some part of the vessel and at a point below the floor, and a pulley upon said deflector-shaft below the step, substantially as described. 60
14. In a centrifugal separator, the combination of a treatment vessel rotatable about a vertical axis, a hollow shaft extending from
- the lower end of the vessel through the floor 40 upon which the separator is supported and there stepped in a suitable bearing and provided with a pulley, an independently-rotatable and longitudinally-movable deflector within the treatment vessel, a shaft therefor 45 extending through the shaft and step of the vessel and journaled in some part of said vessel and at a point below the floor, a pulley upon said deflector-shaft below the vessel step, a step for the lower end of the deflector- 50 shaft, and mechanism below the floor for reciprocating said step, substantially as described.
15. In a centrifugal separator, the combination of a treatment vessel rotatable about a vertical axis and supported upon a bearing below its upper head, an independently-rotatable deflector in said vessel journaled in a bearing on the under side of the head, a feed-receptacle upon the upper side of said head, 60 and openings at or near the periphery thereof into the vessel, substantially as described. 55
16. In a centrifugal separator, the combination of a treatment vessel rotatable about a vertical axis and supported upon a bearing 65 below its upper head, an independently-rotatable deflector in said vessel journaled in a bearing on the under side of the head, a feed-receptacle upon the upper side of said head, 70 openings at or near the periphery thereof into the vessel, and sleeves carried by the upper head and the deflector interposed between the openings and the bearing.
